UNITED STATES PATENT OFFICE.

LAWRENCE M. PINCKNEY, OF CHARLESTON, SOUTH CAROLINA.

RAZOR-BLADE SHARPENER.

1,201,094.

Specification of Letters Patent.

Patented Oct. 10, 1916.

Application filed February 7, 1916. Serial No. 76,684.

To all whom it may concern:

Be it known that I, LAWRENCE M. PINCKNEY, a citizen of the United States, residing at Charleston, in the county of Charleston and State of South Carolina, have invented certain new and useful Improvements in Razor-Blade Sharpeners; and I do hereby declare the following to be a full, clear, and exact description of the invention, such as 10 will enable others skilled in the art to which it appertains to make and use the same.

The present invention relates to improvements in razor blade sharpeners in which rotating stroppers are provided to engage with 15 opposite sides of each cutting edge of double-edged safety razor blades.

It is an object of the present invention to provide an improved razor blade sharpener which will be of simple construction, economical of manufacture, easily operated, and constructed for convenient and quick 20 insertion and removal of the razor blades between the rotating stroppers, which are mounted in pairs in the body and cover, respectively, of a two-part casing.

With these and other objects in view the invention consists in the novel details of construction and combination of parts more fully hereinafter disclosed and particularly 25 pointed out in the claims.

In the accompanying drawings forming a part of this application, and in which similar reference symbols indicate corresponding parts in the several views: Figure 1 is a side 30 elevational view, partly in section, of an improved razor blade sharpener constructed in accordance with the present invention and illustrated with the cover raised. Fig. 2 is a top plan view of the improved device with 35 the cover removed. Fig. 3 is a transverse sectional view taken on the line 3—3 of Fig. 2 and with the cover in place. Fig. 4 is a longitudinal sectional view taken on the line 4—4 of Fig. 2 and with the cover in position. Fig. 5 is a longitudinal sectional view 40 through one of the rollers or stroppers; and Fig. 6 is a perspective view on a reduced scale of the casing with the cover removed and before the stroppers have been mounted 45 therein.

Referring more particularly to the drawings, 1 designates a casing and 2 a cover therefor disconnected from the casing and

removable therefrom. The casing 1 is provided with angle posts 3, fitted in the corners thereof, as indicated plainly in Figs. 2 and 6; such posts extending to a height upwardly therefrom substantially equal to the depth of the cover 2, which latter receives and is guided by the same when moving to 60 position to inclose the casing 1.

Along the longitudinal center of the casing 1 is arranged a series of pins 4 recessed and threaded at their bases to receive screws 5 fitted through countersunk perforations in the base of the casing 1, and whereby the pins 4 are removably mounted therein. These pins may be in any number and are adapted to receive the perforations formed in razor blades, such as shown at 6 in Fig. 70 2, of the Gillette and other types; and the razor blade 6 is slideable vertically on said pins 4, being unsupported centrally and having the lower faces of its opposite cutting edges freely resting upon the leather or 75 other abrading surfaces 7 of wooden or other rollers, or rotating stroppers 8 and 9. (See more particularly Fig. 5). These rollers or rotating stroppers 8 and 9 are disposed in the casing 1 to either side of the 80 series of pins 4, they being mounted on square or other shafts 10 and 11 formed, as disclosed to advantage in Fig. 5, with round journals 12 and 13, which may be fitted in pairs of bearings 14 and 15 or directly in 85 the end walls of the casing 1, as may be deemed better in practice. Coöperating with the rollers or rotating stroppers 8 and 9 of the casing 1, are a similar pair of stroppers 16 and 17 having leather or other suitable 90 abrading faces 18 and 19, and being supported to freely revolve in the cover 2 on square or other shafts 20 and 21 formed with round journals fitted in spring brackets 22 and 23 95 extending across the ends of the cover 2 and being offset centrally, as may be seen in Fig. 4; they having their ends bent inwardly and perforated, as at 24 and 25 in Fig. 1, to receive fastening means. It will be understood that the stroppers 16 and 17 may be 100 readily engaged and disengaged with the bearing brackets 22 and 23 by pressing the same inwardly against the respective end walls of the cover 2.

The several rollers or rotating stroppers 105 10, 11, and 16, 17, are connected to be driven

in unison through gear wheels 26, 27, and 28, 29, secured, by screws or other means 30, (see Fig. 5), to their respective stroppers and being mounted at both ends of the 5 stroppers, which will be appreciated from an inspection of Figs. 2 and 4.

To the lower stroppers 8 and 9 are also connected pinions 31 and 32; the pinion 31 being disposed in mesh with a driving gear 10 33, which also meshes with a pinion 34, connected to drive pinion 32 on the stropper 9. The driving gear wheel 33 is actuated from a crank handle 35 extending on the exterior of the casing 1 and fitted on the projecting end of a shaft 36, on which the driving gear 33 is fixed, the shaft 36 extending across the casing, as will appear from Fig. 2, it being understood that there is a similar driver and driven mechanism located in 15 conjunction with both ends of the rollers 8 and 9. The pinion 34 is journaled on a stub shaft 37 mounted at one end in the adjacent end of the casing 1 and at the opposite end in bracket 38, extending to the shaft 36 and 20 assisting to support the same, the bracket 38 being provided with a bent-over basal flange 39 whereby the same is secured to the bottom of said casing.

In order to prevent injury to the cutting 30 edges of the blade by reverse rotation of the stroppers, the mechanism may be positively prevented from retrograde movement by a pawl 40 pivoted in the bottom of the casing 1, and having a beveled free end engaging 35 with the teeth of the driving gear 33 and resting against a block 41, being yieldably held there-against by a spring 42 which will permit the pawl to be moved and allow the passage of the teeth when the driving gear 40 is rotated in a clockwise direction; but which will prevent the gear wheel being rotated in a counterclockwise direction, as will be clearly understood.

The operation of the invention is conducted substantially as follows: The cover 45 2 being entirely removed, the razor blade 6 is positioned with its perforations occupied by the pins 4 and is allowed to descend there-over until the lower faces of its opposite 50 cutting edges rest upon the stroppers 8 and 9. (See Fig. 2). The cover 2 is therupon brought to engage the guide posts 3 in substantially the manner indicated in Fig. 1, and such guide posts will insure the proper 55 centering of the cover upon the casing as is necessary in bringing the gear wheels into proper meshing engagement. From the position shown in Fig. 1 the cover is permitted to descend to close the casing, as shown in 60 Figs. 3 and 4, and when in position, the gear wheels 28 on the opposite ends of the roller 16 will be brought into mesh with the gear wheels 26 on the roller 8; and the gear wheels 29 on the stropper 17 be similarly 65 brought to engage the gear wheels 27 on the

stropper 9. This engagement can be accurately and securely preserved by resting the left hand upon the cover 2 during operation, while the crank handle 35 is continuously rotated by the right hand.

It will be seen that when the cover 2 is in the position shown in Figs. 3 and 4, the stropping surfaces 18 and 19 of the rollers 16 and 17 will be in contact with the abrading surfaces of the rollers 8 and 9, and will clamp the opposite faces of both edges of the blade 6 therebetween and will be simultaneously operative upon all four faces of the blade to sharpen the same uniformly.

From the arrangement of gearing the several stropper rollers will be rotated each in a direction with respect to the blade edges away from the center, each superposed pair of rollers rotating in opposite directions. In this manner both edges of a double blade 80 6 can be simultaneously sharpened, on both faces, by a few turns of the handle 35; and when the operation is completed for each successive blade, the cover 2 may be readily lifted from engagement with the casing 1, 90 and, when removed, the blade 6 may be readily withdrawn from the pins 4 and a succeeding blade inserted quickly and without loss of time, the cover 2 being thereupon replaced and the operation of stropping such 95 succeeding blade directly proceeded with.

It is obvious that those skilled in the art may vary the details of construction and arrangements of parts without departing from the spirit of my invention, and therefore I, 100 do not wish to be limited to such features, except as may be required by the claims.

I claim:

1. In a razor blade sharpener, the combination of a casing, stroppers in said casing, guide posts on said casing, a cover slidable on said guide posts, resilient bearings in said cover, stroppers journaled in said bearings, and connections for actuating said several stroppers, substantially as described.

2. In a razor blade sharpener of the character described, the combination of a casing, guide posts projecting from said casing, a cover slidable on said guide posts for inclosing the casing, supplemental stroppers mounted in said casing and cover for receiving and supporting a razor blade therebetween, and means for operating said stroppers, substantially as described.

3. In an improved razor blade sharpener, 120 the combination of a casing, guide means projecting from said casing, a cover slidable on said guide means for inclosing the casing, a plurality of stroppers mounted in said casing and cover, means for centering a razor blade to be supported between said stroppers, and means for operating said stroppers, substantially as described.

4. In an improved razor blade sharpener, 125 the combination of a casing, guide posts on

said casing, a cover slidable on said guide posts, complemental pairs of stropers in said casing and cover for supporting a razor blade therebetween, gear wheels connecting said elements for simultaneous operation, pins in said casing for centering a razor blade therein, a crank handle on the

exterior of said casing, and gear connections between said crank handle and the stropers in said casing, substantially as described.

In testimony whereof, I affix my signature.

LAWRENCE M. PINCKNEY.
